US0D1085134S

(12) **United States Design Patent** (10) **Patent No.:** **US D1,085,134 S**
(45) **Date of Patent:** **** Jul. 22, 2025**

(54) **DISPLAY SCREEN OR PORTION THEREOF WITH GRAPHICAL USER INTERFACE**

(71) Applicant: **Salesforce, Inc.**, San Francisco, CA (US)

(72) Inventor: **Alwin Mulyono**, Montara, CA (US)

(73) Assignee: **Salesforce, Inc.**, San Francisco, CA (US)

(**) Term: **15 Years**

(21) Appl. No.: **29/926,115**

(22) Filed: **Jan. 29, 2024**

Related U.S. Application Data

(63) Continuation of application No. 29/911,955, filed on Sep. 12, 2023.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The dashed broken lines in the figures show a display screen or portion thereof, and form no part of the claimed design. The dot-dash broken lines in the figures and the areas within the dot-dash broken lines show portions of the graphical user interface that form no part of the claimed design.

1 Claim, 2 Drawing Sheets
